DESIGN FOR A GEAR CASING FOR A CEN- TRIFUGAL LIQUID SEPARATOR

Clifford E. Butler, Waterloo, Iowa

Application August 8, 1938, Serial No. 79,189

Term of patent 14 years

To all whom it may concern:

Be it known that I, Clifford E. Butler, citizen of the United States, residing at Waterloo, in the county of Blackhawk and State of Iowa, have invented a new, original, and ornamental Design for a Gear Casing for a Centrifugal Liquid Separator, of which the following is a specification, reference being had to the accompanying drawing, forming part thereof.

Fig. 1 is a top plan view of the gear casing for a centrifugal liquid separator, showing my new design.

Fig. 2 is a side elevation of the same.

Fig. 3 is an end view of the same.

I claim:

The ornamental design for a gear casing for a centrifugal liquid separator, as shown.

CLIFFORD E. BUTLER.
